EMERGENCY LIGHT AND WATER
CONTAINER THEREFOR

Charles Linhardt, Jr., Baltimore, Md.

Application February 6, 1937, Serial No. 124,454

1 Claim. (Cl. 48—35)

This invention relates to certain new and useful improvements in an emergency light and container therefor, and is particularly adapted for construction work or for railroads and embodies a light and its container that can be quickly made available and one which can be produced at a comparatively small cost.

A still further object of the invention is the provision of an emergency light having a carbide 10 casing and a container in which the carbide casing is inserted, and means to retain the latter in fixed resilient position within the container.

A still further object of this invention is the provision of an emergency light, efficient in operation and one that can be quickly assembled and made ready for use at all times.

A still further object of this invention is the provision of an emergency light and container therefor, which container is adapted to be filled 20 with water and to retain the casing of the light proper in fixed position therein, and ready for use in any emergency in construction or railroad work.

With these and other objects in view, the invention consists in certain novel features, combination and arrangement of parts as will be hereinafter more fully described, pointed out in the accompanying drawing, and claimed.

In the drawing,

30 Figure 1 is a vertical, longitudinal, sectional view of the casing and container, with the container partly broken away, illustrating the device as made in accordance with this invention;

Figure 2 is a perspective view of the container 35 and casing in fully assembled position;

Figure 3 is a transverse sectional view, taken on the line 3—3 of Figure 1; and,

Figure 4 is an enlarged, fragmentary, sectional view, taken on the line 4—4 of Figure 3.

40 Referring to the drawing, the numeral 5 indicates a casing in the form of a cylindrical shell having a bottom portion 6 and top portion 7, all soldered or welded together to form an air and water tight casing, as clearly illustrated in Figure 1. The bottom 6 of the casing 5 is provided with an opening 8, through which opening water is admitted into the casing, the purpose of which will be hereinafter more fully described. The top 7 of the casing 5 is provided centrally with open-

45 ings 10, which coincide with the opening 8 for the purpose of permitting gas generated in the casing 5 to escape therethrough to the atmosphere and to be ignited at that point. The opening 8 of the bottom 6 is normally closed by a 50 removable tab 11 sealed thereto to normally close

the opening against air and water until ripped therefrom by virtue of the handle portion 12.

The openings 10 in the top 7 are normally closed in an air and water tight condition by a cap 13 provided with a handle 14 to permit the cap to be readily removed therefrom, the purpose of which will be hereinafter more fully described.

A supporting tube 15 has its lower open end secured around the opening 8 in the bottom 6 of the casing and projects upwardly in a vertical position within the casing 5. Its upper closed end 16 is provided with openings 17 which establish a communication between the exterior of the casing and interior thereof by virtue of the opening 8 and openings 17, the purpose of which will 15 be hereinafter more fully described.

A perforated tube 18 is secured by one end to the interior of the bottom 6 of the casing 5 and completely surrounds the member 15, extends upwardly and vertically through the casing 5 and 20 has its upper end secured to the interior of the top 7 surrounding the openings 10 therein. The purpose of this tube is to protect and prevent the openings 17 and 8 from becoming clogged or choked up by the mushy detritus of the spent carbide, as will be hereinafter more fully described.

Surrounding the tube 18, near its central portion, is an annular disc 19, and it is secured to said tube in such a manner as to separate the casing 5 into a gas chamber 20 and a carbide chamber 21, and the latter chamber has placed therein suitable carbide "A."

The diameter of the disc 19 is such as to permit 35 gases formed in the carbide chamber to pass between its peripheral edge and the interior wall of the casing and to pass up into the chamber 20. It is also to be understood that gases generating in the carbide chamber will pass up through the tube 18 into the chamber 20 and through the openings 10 of the top 7.

When it is desired to use the structure described, it is only necessary to place the casing 5 in a container of water. Prior to placing the same therein, the tab 11 and cap 13 are ripped 45 from their respective covers by virtue of the handles 12 and 14 thereof. Water entering through opening 8 is forced upwardly through openings 17, out through the perforations of the tube 18 into the carbide "A", gas generating therein passes up through the tube and around the peripheral edge of the baffle 19 into the chamber 20, and when sufficient gases are generated 50 in chamber 20 they pass back through tube 18, 55

out the openings 10 where they are ignited at that point.

Now, to provide a container for this emergency light I have provided an open end receptacle 22 having its bottom fully closed, as at 23, and its open end provided with an entrance opening 24 of a diameter slightly larger than the casing 5. The inturned flange 24, constituting the entrance opening of the open end of the receptacle 22, definitely positions the casing 5 centrally within the receptacle 22.

To normally center and retain the casing 5 in fixed position within the receptacle 22, I have secured in said receptacle on its side and bottom walls, resilient supporting elements 25, which are secured to the bottom and side walls of the receptacle 22, as at 26, by any fastening elements suitable for the purpose.

The resilient supporting elements 25 firmly hold the casing 5 in fixed relation about the central axis of the receptacle 22 and also hold the casing 5 in proper position with relation to the open end thereof, as can be clearly seen in Figure 1 of the drawing. The receptacle is also provided exteriorly with a suitable handle 27, which renders the same portable and permits it to be easily transported from place to place and put in proper position when it is desired to use the same.

And to retain and lock the casing 5 in the receptacle 22, there is provided a turn catch 28, pivoted as at 29, to the top of the receptacle 22, one end constituting a handle and its free end constituting a retaining member to hold the casing 5 against vertical movement within the receptacle 22.

The receptacle 22 is to be approximately filled with water and the casing 5 fastened therein. When it is desired to use the emergency light it is

only necessary to turn the catch 28, lift the casing from the receptacle 22, rip the tab 11 and cap 13 therefrom, reinsert the casing in the receptacle 22, which submerges it in the water contained therein, refasten the catch 28 and 5 ignite the generated gases emanating from the openings 10 of the casing.

The action of this emergency light in operation is practically identical with the structures claimed in co-pending applications Serial Nos. 10 124,451 (now Patent No. 2,120,523), 124,452 and 124,453, executed and filed of even date herewith, the only exception being the container and the construction of the tube 18.

While I have described one embodiment of the 15 invention, it is to be understood that various changes might be made in the construction, combination and arrangement of parts, without departing from the spirit of the invention as 20 claimed.

Having thus described my invention, what I claim as new is:

A portable emergency light and water container therefor, comprising a carbide casing having a water entrance and gas exit therein, removable closures for the entrance and exit, a perforated supporting tube secured to the entrance and extending upwardly in the casing, a perforated conveying tube secured to and about the first named tube and having its free ends secured to 30 and about the entrance and exit openings, and a portable water container provided with interior flexible means to receive and retain said carbide casing in vertical position in said container so that the device may be held against displacement 35 in transit.

CHARLES LINHARDT, JR.
